UNITED STATES PATENT OFFICE

FREDERICK M. VENZIE, OF PHILADELPHIA, PENNSYLVANIA

BUILDING CONSTRUCTION

Application filed December 20, 1930. Serial No. 503,635.

This invention, generally stated, relates to a building structure and has more especial relation to ceiling slabs as utilized in connection with a building construction.

5 One object of the present invention is to provide a ceiling structure in which pre-cast slabs of cementitious material have interlocked relation both longitudinally and laterally considered whereby the ceiling slabs 10 have continuous reinforced connection from end to end of a building both throughout its length and breadth.

Another object of the present invention is to provide a ceiling construction in which 15 pre-cast slabs have interlocked connection at their ends by means of knuckle-joint arrangement of parts.

A further object of the present invention is to provide a ceiling construction in which 20 pre-cast slabs longitudinally considered are re-inforced in a continuous manner throughout the length of a building by means of an angle iron, ladder-like construction with adjacent slabs tied or coupled together laterally throughout the breadth of a building.

A further object of the present invention is to provide a ceiling structure of the character stated in which means is provided for readily suspending pre-cast ceiling slabs even 25 though the floor members may not be evenly spaced.

A still further object of the present invention is to provide means for engaging the longitudinal edges of adjacent edges of pre-cast ceiling slabs intermediate spaced floor members to prevent buckling at such points as are not directly supported by the floor members.

A still further object of the present invention is to provide a novel form of pre-cast ceiling slab suspending clip which is capable of use either in connection with properly spaced floor members or auxiliary members as supported from flooring.

45 A still further object of the present invention is to provide a ceiling construction of the character stated in which unskilled labor may readily and expeditiously assemble ceiling slabs of pre-cast cementitious material.

50 A still further object of the present in-

vention is to provide a structure of the character stated which is simple, efficient, and relatively inexpensive to manufacture, the various parts being made at a central plant for shipping to point of erection ready for 55 assembling.

Other and further objects of the present invention reside in the provision of general details of construction and in the arrangement, combination, and connection of parts 60 for attaining the results sought by the foregoing objects.

The invention consists of the novel construction hereinafter described and finally 65 claimed.

The nature, characteristic features and scope of the invention will be more fully understood from the following description taken in connection with the accompanying drawings forming part hereof, and in which: 70

Fig. 1 is a view principally in longitudinal section of pre-cast ceiling slabs as supported from floor members;

Fig. 2 is a view in cross section of a pair of the ceiling slabs shown in Fig. 1, as tied 75 or coupled together;

Fig. 3 is a view in end elevation of one of the ceiling slabs;

Fig. 4 is a view in perspective of one of the ceiling slab supporting clips shown in 80 Fig. 1;

Fig. 5 is a view taken upon the section line 5—5 of Fig. 1;

Fig. 6 is a view as seen from the under-side of pre-cast slabs coupled or tied together;

Fig. 7 is a longitudinal edge view of one of the slabs;

Fig. 8 is a view in side elevation of a metal clip for coupling together pre-cast ceiling 85 slabs laterally;

Fig. 9 is an end view of Fig. 8; and

Fig. 10 is a fragmentary view in cross-section illustrating a slightly modified manner of coupling together adjacent ceiling 95 slabs.

For the purpose of illustrating my invention I have shown in the accompanying drawings two forms thereof which are at present preferred by me, since the same have 100

been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring now to the drawings in detail, 10 and with more especial relation first to Figs. 1 to 9 inclusive, the reference numeral 11 designates a floor of cementitious material supported upon floor members 12, usually I-beams, which may be or may not be equally spaced apart, and which as practice dictates are not usually found equally spaced. This is particularly true when it becomes necessary to introduce a girder designated 13 in connection with the flooring. It also happens that it sometimes becomes necessary to introduce a plasterer's channel 14 between a pair of floor members. Having these conditions in mind it is of the essence of the present invention that means be provided to properly suspend, with respect to the flooring 11, pre-cast ceiling slabs 15 of cementitious material. Each slab 15 has embedded therein a reinforcement comprising a ladder-like structure made up of spaced, parallel, longitudinal angle-irons 16 of inverted L-shape, connecting which angle-irons are cross-members 17, usually of relatively heavy wire, the terminus of each cross-member being bent over the tops of the angle-irons 35 as at 18, see Fig. 2. Each slab 15 is provided at each end with spaced fingers 19 slightly bevelled, as shown best in Fig. 3, for co-operatively engaging similar fingers of an adjoining slab, as is clearly illustrated in 40 Fig. 5, to interlock the slabs longitudinally considered from end to end of a building structure. Each ceiling slab, longitudinally considered, is grooved as at 20 to accept the fingers of metal clips best seen in Figs. 4 45 and 8, a description of which will presently be given. Each slab is also provided along its longitudinal edges with spaced, vertically disposed slots 21, across which the angle-irons 16 extend as best seen in Fig. 6. When the 50 ceiling slabs are positioned side by side and end to end as clearly shown in Fig. 6, the wires 22 are employed for coupling together adjacent slabs, thus providing an interlock of re-inforced parts throughout the width 55 of the building. The tie-wires 22 are passed through apertures formed in the vertical bars of the angle-irons 16, best seen in Fig. 2. The longitudinal edges of the slabs are also provided with ribs 23 and grooves 24 to complete an interlock of parts laterally. The 60 ceiling slabs in practice are further coupled together or interlocked by means of metal clips, as best seen in Figs. 8 and 9. The clip is designated by reference numeral 25 and is stamped from a single blank so as to provide

a vertically disposed bar 26. Extended thereto from at right angles thereto are horizontally opposed fingers 27 the lower-most ones of which are adapted to engage in the grooves 20 of the ceiling slabs, and the upper-most ones of which are adapted to engage over the top faces of adjacent slabs, as best seen in Fig. 5. The ceiling slabs are suspended from the floor members by means of a reversible clip, best seen in Fig. 4. Each clip is stamped from a single blank and comprises a vertically disposed plate 28 having opposed notched portions 29 and 30. In use the notched portion 29 of a clip is caused to engage over the lower flange of an I-beam 12, as best seen in Fig. 1. However, in case it is necessary, because the floor supports are not properly spaced, to make use of an auxiliary floor member 31 to support a small channel 32, then the notched portion 30 of a clip is caused to engage over the channel 32. In either case the fingers 33 of plate 28 are caused to engage over the upper surface of a ceiling slab and the fingers 34 are caused to engage the grooves 20 of adjacent slabs for suspending the latter from a floor member. It is to be observed that the fingers 33 and 34 are arranged at right angles to the plate 28 and are disposed in different horizontal planes. The plate 28 of a clip is provided with opening 35 whereby the latter may be nailed to place with respect to a ceiling slab. In some instances it may be advisable to employ small channel-irons 14 between the floor members in order to suspend adjacent ends of the ceiling slabs. In such case I make use of metal, hook-like members 36 for engaging over the channel-irons and beneath wires 17 embedded in the slabs 15. In the connection it is to be noted that apertures may be formed upon the top faces of the slabs in order that the bottoms of the hook-like members 36 may be caused to engage the wires 17.

The construction disclosed in Fig. 10 is similar in all respects to that disclosed in the other figures, with the exception that the angle-irons 16 forming part of the ladder-like reinforcement are secured or tied together by means of tie-wires 38 having swivelled cross rods 39 whereby when the tie-wires of the cross-rods 39 are introduced through apertures in the tops of the slabs to permit the cross-rods to rest upon the slab tops and the terminus of the tie wires twisted together beneath the angle-irons 16 of the reinforcement, a complete and efficient interlock of ceiling slabs is obtained.

What is claimed is:

1. In a ceiling structure of the character stated, floor members of metal having flanged portions, pre-cast ceiling slabs of cementitious material arranged beneath said floor members end to end in abutting relation, said abutting ends having interlocked relation one with another, the sides of said ceil-

- ing slabs having longitudinal grooves therein, and metal clips for suspending said ceiling slabs from said floor members, each clip comprising a flat plate having extended 5 therefrom at right angles fingers for engaging in the grooves of said slabs and being notched in a plane above said fingers to engage over the flanged portion of said floor members.
- 10 2. In a ceiling structure of the character stated, floor members of metal having flanged portions, pre-cast ceiling slabs of cementitious material arranged beneath said floor members end to end in abutting relation, 70 said abutting ends having interlocked relation one with another, the sides of said ceiling slabs having longitudinal grooves therein, a reinforcement of ladder-like form embedded in each slab, the side rails of said reinforcement paralleling the slab sides, tie wires connecting the side rails of adjacent slabs to form an interlock, the side walls of said slabs being cut away at intervals upon the under faces of said slabs to permit connection of 75 said tie-wires, and metal clips for suspending said ceiling slabs from said floor members, each clip comprising a flat plate having extended therefrom at right angles fingers for engaging in the grooves of said slabs and being notched in a plane above said fingers to engage over the flanged portion of said floor members.
- 15 3. In a ceiling structure of the character stated, floor members of metal having flanged portions, pre-cast ceiling slabs of cementitious material arranged beneath said floor members end to end in abutting relation, 80 said abutting ends having interlocked relation one with another, the sides of said ceiling slabs having longitudinal grooves therein, a reinforcement of ladder-like form embedded in each slab, the side rails of said reinforcement paralleling the slab sides, and tie wires connecting the side rails of adjacent slabs to form an interlock, the side walls of said slabs being cut away at intervals upon the under faces of said slabs to permit connection of 85 said tie-wires, and metal clips for suspending said ceiling slabs from said floor members, each clip comprising a flat plate having extended therefrom at right angles fingers for engaging in the grooves of said slabs and being notched in a plane above said fingers to engage over the flanged portion of said floor members.
- 20 4. In a ceiling structure of the character stated, floor members of metal having flanged portions, pre-cast ceiling slabs of cementitious material arranged beneath said floor members end to end in abutting relation, 90 said abutting ends having interlocked relation one with another, the sides of said ceiling slabs having longitudinal grooves therein, metal clips for suspending said ceiling slabs from said floor members, each clip comprising a flat plate having extended therefrom at right angles fingers for engaging in the grooves of said slabs and being notched in a plane above 95 said fingers to engage over the flanged portion of said floor members, plasterer's channels arranged between adjacent floor members, and hooks arranged at the ends of said slabs for engaging said plasterer's channels.
- 25 5. In a ceiling structure of the character stated, floor members of metal having flanged portions, pre-cast ceiling slabs of cementitious material arranged beneath said floor members end to end in abutting relation, 100 said abutting ends having interlocked relation one with another, the sides of said ceiling slabs having longitudinal grooves therein, a reinforcement of ladder-like form embedded in each slab, the side rails of said reinforcement paralleling the slab sides, tie wires connecting the side rails of adjacent slabs to form an interlock, and metal clips for suspending said ceiling slabs from said floor members, each clip comprising a flat plate having extended therefrom at right angles fingers for engaging in the grooves of said slabs and being notched in a plane above 105 said fingers to engage over the flanged portion of said floor members, plasterer's channels arranged between adjacent floor members, and hooks arranged at the ends of said slabs for engaging said plasterer's channels.
- 30 6. In a ceiling structure of the character stated, floor members of metal having flanged portions, pre-cast ceiling slabs of cementitious material arranged beneath said floor members end to end in abutting relation, 110 said abutting ends having interlocked relation one with another, the sides of said ceiling slabs having longitudinal grooves therein, metal clips for suspending said ceiling slabs from said floor members, each clip comprising a flat plate having extended therefrom at right angles fingers for engaging in the grooves of said slabs and being notched in a plane above 115 said fingers to engage over the flanged portion of said floor members, plasterer's channels arranged between adjacent floor members, and hooks arranged at the ends of said slabs for engaging said plasterer's channels.
- 35 7. In a ceiling structure of the character stated, floor members of metal having flanged portions, pre-cast ceiling slabs of cementitious material arranged beneath said floor members end to end in abutting relation, 120 said abutting ends having interlocked relation in knuckle-joint fashion one with another, the sides of said ceiling slabs having longitudinal grooves therein, and metal clips for suspending said ceiling slabs from said floor members, each clip comprising a flat plate having extended therefrom at right angles fingers for engaging in the grooves of said slabs and being notched in a plane above 125 said fingers to engage over the flanged portion of said floor members.
- 40 8. In a ceiling structure of the character stated, floor members of metal having flanged portions, pre-cast ceiling slabs of cementitious material arranged beneath said floor members end to end in abutting relation, 130 said abutting ends having interlocked relation one with another, the sides of said ceiling slabs having longitudinal grooves therein,
- 45
- 50
- 55

and metal clips for suspending said ceiling slabs from said floor members, each clip comprising a flat plate having extended therefrom at right angles fingers for engaging in the grooves of said slabs and being notched in a plane above said fingers to engage over the flanged portion of said floor members, said slabs being formed to have tongue and groove connection with one another along their longitudinal edges.

9. A construction as described in claim 1 characterized by each pre-cast ceiling slab having embedded therein a reinforcement of substantially ladder-like configuration the side rails of which are formed of angle-irons.

10. A construction as described in claim 1 characterized by each pre-cast ceiling slab having embedded therein a reinforcement of substantially ladder-like configuration the side rails of which are formed of angle-irons, the side walls of each said slab being undercut at spaced intervals to permit tying together of the side rails of companion slabs.

11. A construction as described in claim 1 characterized by said interlocked portions being formed of beveled tenons.

12. A construction as described in claim 2 characterized by plasterer's channels arranged intermediate of said floor members, and hook-like members engaging over the tops of said plasterer's channels and beneath the cross-rods of said ladder-like reinforcement.

13. A construction as described in claim 2 characterized by apertures extending entirely through said slabs for accommodating hook-like members for engaging over plasterer's channels introduced intermediate of said floor members and beneath the cross-bars of said ladder-like reinforcement.

In witness whereof, I have hereunto signed my name.

FREDERICK M. VENZIE.
